UNITED STATES PATENT OFFICE.

ISAAC HARTER, OF DONGAN HILLS, NEW YORK, ASSIGNOR TO THE BABCOCK & WILCOX COMPANY, OF BAYONNE, NEW JERSEY, A CORPORATION OF NEW JERSEY.

STEAM BOILER.

Application filed March 30, 1922. Serial No. 548,185.

My present invention relates to water-tube boilers in which some or all of the tubes are subjected to an intense heat. Under such conditions, particularly the tubes adjacent to the fire may become weakened by blistering, and it is one of the objects of my invention to provide a construction which will minimize this difficulty.

My invention will best be understood from the following description and the appended drawing, in which Fig. 1 is a partial sectional elevation of a water-tube boiler which I have chosen for purposes of illustration; Fig. 2 is an enlargement of a portion of one of the headers shown in Fig. 1, with the end of the tube expanded therein, Fig. 3 is an enlarged cross-section through one of the headers and the end of a tube inserted therein, showing a step in the expansion of the tube into the header, and Fig. 4 is a fragmentary section through a portion of a header showing one of the tubes of the lowermost row and tubes of other rows expanded therein.

Like reference characters refer to like parts in the several views.

The illustrative form of boiler has uptake headers 10 and downtake headers 11 connected by horizontally inclined water tubes arranged in rows in the usual manner. The lowermost row 12 is exposed for its entire length to the direct radiant heat of the furnace, while the row 13 above it is protected from such heat to a degree by the row of tubes 12. Extending along the row 13 is a baffle 14, from the end of which extends upwardly a vertical baffle 141, the boiler also being provided with a cross baffle 15, as usual, the baffles being arranged so that the gases flow across the entire length of the lowermost rows of tubes and then back and forth across the remainder of the tubes to a gas outlet.

The lowermost rows of tubes, particularly the row 12, being subjected to the direct heat of the furnace, such tubes may be blistered or otherwise destroyed much more quickly than the tubes above them. It has heretofore been proposed to lengthen the life of such tubes by making the walls thereof heavier. With such thick-walled tubes, however, the hole in the header or water chamber in which the tube is expanded is subjected to much greater pressure during the expansion of the tube than exists when relatively thin-walled tubes are used, and particularly where

tubes are replaced from time to time, this increased pressure tends to enlarge the hole and finally makes it impossible to expand a tube properly in it.

By my invention, I overcome this difficulty by providing a thin-walled end portion in a tube having walls thicker than usual, this thinning of the walls being done from the inside of the tube. Consequently, the exterior diameter of the tube before the ends are expanded is the same throughout its length, the internal diameter at the ends being larger for a short distance from each end than the internal diameter of the main portion of the tube.

In Fig. 2, I have shown one of the tubes 12 expanded into a header 10, the tube having a thin-walled section from its end to the point 16 and the end of the tube having been expanded into the tube hole in the header.

In Fig. 3, the effect on this thin-walled section produced by expanding the end into the header is illustrated. In this view the expanding tool T has been operated until its rollers R have expanded the end of the tube as shown in the drawing, the thin-walled section extending far enough beyond the front face of the header 10 to give space for the action of these rollers on either side of the wall of the header.

In practice, I prefer to make all of the tubes of the boiler of the same external diameter and to have some only of the tubes having the two-internal-diameter construction. For instance, in the arrangement shown, the row of tubes 12 is the only one having thick walls, and yet the external diameter of these tubes is the same as that of the remainder of the tubes in the boiler.

The thickness of the wall of the thin-end portion of the thick-walled tubes is preferably of the same thickness as the thickness of the walls of the remaining tubes of the boiler. Consequently, the effect in expanding the ends of these thick-walled tubes into the header is exactly the same as if the tube had the normal thickness of wall, and, at the same time, by having the thick-walled portion, the life of the tube is greatly increased and its tendency to blister reduced.

By keeping the external diameter of the tube substantially uniform throughout its length and making the variations in the thickness of the wall by changes in the internal

diameter, the tube may be entered and withdrawn from the tube holes in the headers or water chambers in the usual manner.

While I have illustrated the water tubes with the thin-walled end portion in connection with a boiler having horizontally inclined water tube, it will be understood that the construction may also be used in boilers in which the tubes extend more or less vertically and are entered into water drums.

I claim:—

1. In a water-tube boiler, water chambers and water tubes connected to said chambers with their ends expanded into the walls of the chambers, certain of said tubes having end portions with walls thinner than the walls of the remaining portions of such tubes, and others of the tubes having a substantially uniform wall thickness throughout which is less than that of the body portions of the tubes having thinned end portions, the exterior diameters of all portions of the tubes being substantially uniform throughout their length, and all of the tubes having substantially the same external diameter.

2. In a water tube boiler, a water chamber having a plurality of water tube holes therein, all of the holes being of the same diameter, and water tubes, all of said tubes having the same external diameter throughout their length and some of said tubes having an integral end portion of substantially the same external diameter as the main body portion of the tube, but of less thickness than the said main body portion, and others of said tubes having a wall thickness substantially uniform throughout but less than that of the body portions of those tubes having thinned ends, all of said tubes being expanded at their ends in the holes in said water chamber.

3. In a water tube boiler, a water chamber having a plurality of water tube holes therein, all of the holes being of the same diameter, and water tubes, all of said tubes having the same external diameter and some of said tubes each having an integral end portion of substantially the same external diameter as the main body portion of the tube, but of less thickness than the said main body portion, said end portion being expanded in one of said tube holes, the relatively thin wall of said last-named tubes extending from the end of the tube to a point spaced from the

outer surface of said water chamber, and others of said tubes having a wall thickness substantially uniform throughout but less than that of the body portions of those tubes having thinned ends, all of said tubes being expanded at their ends in the holes in said water chamber.

4. In a water-tube boiler, a water chamber a wall of which is provided with a hole, and a boiler tube having an integral end portion of substantially the same external diameter as the main body portion of the tube, but with its walls of less thickness than the thickness of said main body portion, said end portion being expanded in the hole in said wall.

5. In a water-tube boiler, water chambers and water tubes connected to said chambers with their ends expanded into the walls of the chambers, certain of said tubes having end portions with walls thinner than the walls of the remaining portions of such tubes, and others of the tubes having a substantially uniform wall thickness throughout which is less than that of the body portions of the tubes having thinned end portions, the exterior diameters of all portions of the tubes being substantially uniform throughout their length, and all of the tubes having substantially the same external diameter, and the ends of those tubes with thinned ends having substantially the same wall thickness as the walls of those tubes having a substantially uniform wall thickness.

6. In a water-tube boiler, a water chamber a wall of which is provided with a hole, and a boiler tube having an integral end portion adapted to be expanded in the hole in said wall of substantially the same external diameter as the main body portion of the tube, but with its walls of less thickness than the thickness of said main body portion.

7. In a water tube boiler, a water chamber a wall of which is provided with a hole, and a boiler tube having an integral end portion adapted to be expanded in the hole in said wall of substantially the same external diameter as the main body portion of the tube, but with its walls of less thickness than the thickness of said main body portion, the relatively thin wall of said tube extending from the end of the tube to a point spaced from the outer surface of said water chamber.

ISAAC HARTER.
